UNITED STATES PATENT OFFICE.

DAVID J. SEAMAN, OF SAGINAW, MICHIGAN.

DISPLAY FIXTURE.

Application filed October 5, 1921. Serial No. 505,607.

To all whom it may concern:

Be it known that I, DAVID J. SEAMAN, a citizen of the United States, and a resident of Saginaw, in the county of Saginaw and 5 State of Michigan, have invented a new and useful Improvement in Display Fixtures, of which the following is a full, clear, and exact description.

This invention relates to display fixtures 10 adapted for use in stores or show rooms for displaying garments of any description. The fixture is provided with novel lighting means, and is constructed to show a large number of garments and at the same time 15 occupy a minimum amount of floor space. A number of the fixtures may be arranged to form partitions in the store between which are show rooms or alcoves suitable for dressing or fitting rooms. It is so built as 20 to be very accessible, and has numerous facilities for displaying the garments in different positions and to the best advantage. Means are provided for suspending the garments inside the fixture and distributing 25 them at substantially equal distances. Curtains surround the sides and front of the fixture when not in use for display, and these keep the dust from the garments and are intended to be ornamental. Means are 30 provided for easily operating said curtains.

Other features and advantages will be brought out in the following specification and illustrated in the drawings forming a part hereof and in which—

35 Fig. 1 is a front view, with the curtains withdrawn;

Fig. 2 is a side view, with a portion broken out;

Fig. 3 is a central longitudinal section 40 showing parts in a different position and indicating one of the hangers;

Fig. 4 is a top plan view on a larger scale, showing the operating mechanism, the parts being in the same position as in Fig. 3;

45 Fig. 5 is a sectional plan on the same scale as Fig. 4, taken on the line 5—5 of Fig. 1, looking in the direction of the arrows, the parts being in the same position as in Figs. 3 and 4, and the curtains being omitted;

50 Fig. 6 is an enlarged sectional detail view taken on the line 6—6 of Fig. 2, with parts broken out for economy of space, showing

the horizontal bar for supporting the clothing to be displayed;

Fig. 7 is a detail sectional view taken on 55 the line 7—7 of Fig. 6;

Fig. 8 is a detail elevation showing the forward end of one of the curtains and means for holding it closed;

Fig. 9 is a detail sectional view of the 60 curtain track and curtain-holding means;

Fig. 10 is a detail view of the curtain and 65 slidables members to which the curtain is attached; and

Fig. 11 is a detail sectional view showing 70 a means for providing different colored transparent or translucent materials for the lights to shine through.

The reference numeral 1 designates a back 75 wall which is secured to a base 2, said base being provided with side supports 3, which raise it off the floor and leave the front beneath the base open, so as to make it possible to step close up to the fixture, and also to facilitate cleaning the floor below the fixture. 75

The base has side wings or columns 4 extending upward therefrom in line with the legs 3, which wings support the upper structure which takes care of the lighting effects. Secured on top of the wings 4 and 80 to the back 1 is a shallow box-like structure 5, which houses the operating mechanism, and has set in its front wall 6 a series of windows 7 through which the light shines from a set of electric bulbs 8. A series of 85 windows 7^a in the bottom of the box cast light downward in the fixture. Hinged at 9 to the top of the front of the structure 5 is another box-like part 10, which has windows 11 in its front and rear walls, and 90 other windows 11^a in the bottom wall, through which light may pass from another set of electric bulbs 12.

The box 10 is so hinged and constructed 95 that it may lie on top of the box 5, as in Fig. 2, or may extend outward therefrom, as in Fig. 3, or it could occupy, if desired, any intermediate position.

Mechanism is provided for operating the 100 movable section of the light box, the preferred embodiment of which will now be described. An electric motor 13 in the stationary box section 5 has its shaft 14 connected by a centrifugal clutch 15 with speed-

reducing means 16, which in turn is connected with a shaft 17, suitably supported and journaled in the interior of this box in line with the shaft 14. This speed-reducing means is shown as comprising a small pulley 17^a connected with the clutch, a compound pulley 17^b loose on a shaft 34, hereinafter referred to, a large pulley 17^c fixed on the shaft 17, and belts 17^d passing over the pulleys. The shaft 17 has secured to it a bevel gear 18, which meshes with a bevel 19, which in turn is meshed by a bevel gear 20, which last is loosely mounted on a shaft 21 suitably supported and journaled in line with the shafts 14 and 17. The shaft 21 has splined to it between the miter gears 18 and 20 a sliding groove clutch collar 22, which is engaged by pins on a shifter arm 23 secured to an upright rock-shaft 24. This collar 22 bears familiar teeth or projections 25 and 26 on its opposite ends, to engage alternately with the teeth 27 and 28, respectively, on the bevel gears 18 and 20. Secured on the outer end of the shaft 21 is a worm 29, which engages a worm-wheel 30 fixed on an upright shaft 31. Also fixed on the shaft 31, below the worm wheel 30, is another worm 32, which meshes with a worm-wheel 33 mounted on the shaft 34 which extends horizontally across the entire fixture, projecting at its opposite ends through the sides of the box, and having secured to these ends external arms or levers 35. These arms have swiveled in their outer ends pins 36, which are slidable along bars 37, secured to the box 10.

A hand wheel 38 secured to a vertical shaft 39, passing upward within shaft 31, which is hollow, operates a lever 40 fixed to the upper end of said shaft 39, this lever in turn being pivotally connected to one arm of a bell-crank lever 41, which is fixed to the rock-shaft 24. The other arm of said bell-crank lever bears a projection 42, which is adapted to engage with pins 43 mounted on a disk 44, which is secured to the shaft 34. The shaft 39 is adapted to remain, frictionally or otherwise, in any position to which is turned.

From the foregoing it will be apparent that when the collar 22 is in an intermediate position with its teeth 25 and 26 out of engagement with the teeth 27 and 28 on the bevel gears 18 and 20, the mechanism is in a neutral position, and if the motor is running the said bevel gears will run without doing any work; but when the hand wheel is turned to the right or left the corresponding projections on the clutch collar and gears will engage, the shaft 21 will be driven in one direction or the other, and the box 10 will be moved accordingly. The pins on the disk 43 are so arranged that when the complete movement of the box has been made, either from the open to the closed position

or vice versa, they will automatically, through the bell-crank lever, throw the clutch collar to intermediate or neutral position to prevent damage to the motor or apparatus. Depending upon the position of the box section 10, different natural and artificial lightings of the contents of the fixture can be obtained. When this section is down, it forms in connection with the section 5 a top to keep dust from settling on the garments, the enclosure being completed by the back and the curtains hereinafter referred to, when the garments are not on display. It is also clear from the foregoing that the box section 10 may be stopped, and will remain at any intermediate position between what might be termed the full open or full closed position, as it is often desirable to have the box section 10 at an angle to the fixed top in order to secure a desirable lighting effect.

In the compartment 5 is another motor 45 having a pulley 46 on its shaft and a belt 47 connecting said pulley 45 with another pulley 48, which is secured to a horizontal tube 49 constituting a hanger rod from which are suspended the hangers (Fig. 3), for the clothing to be displayed. The tube 49 extends transversely across the fixture beneath the top, being journaled at its ends in suitable blocks 49^a extending downward from the front under part of the box section 5.

In handling the garments they are likely to become disarranged and bunched together at one or more points along the tube, and as it takes some time to rearrange them under ordinary conditions, I have provided means for automatically distributing them, this being accomplished by rapidly rotating the horizontal hanger tube by suitable means such as described. This rotation has the effect of quickly evening the row of garments and hangers, and when this has been accomplished the rotating mechanism is stopped. Ball bearings 50 are provided for the tube. The rotation of the tube also causes a vibration which tends to free the garments of dust.

Lateral extensions consisting of tubular rods 51 with knobs 52 are nested in the tube 49. These may be pulled out at any time desired, at either or both ends of the main tube, and will then accommodate additional garments; or certain selected garments from the stock on the main tube 49 may be placed on the extensions. Telescopic extension rods 53 adapted to be pulled out in front are also mounted slidably in the side frames, near the main tube. On these extensions garments may be hung in order that a front view of the same may be obtained.

An additional set of lights 54 is located in a back compartment 54^a beneath the rear portion of the stationary light box 5, just back of the windows 7^a. Windows 55 in a front door 56 of this compartment, and in

its lower wall 57, afford additional illumination to the interior of the fixture and its contents.

Curtains 58, which when withdrawn 5 occupy the rearward positions shown in Figs. 1 and 2 at the sides of the fixture, are arranged to enclose the entire sides and front of the garment space and thus keep dust and dirt from gathering on the garments when not being shown. Straight pieces of track 59 secured to the under side of the top section 5 take care of the curtain when it is withdrawn. Another section of track 60 is secured to the folding top section 10, extending across beneath the forward part of this section and curved around and extending rearward at both sides, the construction being such that when the part 10 is thrown down as in Fig. 3 the ends of 20 the track section 60 abut the forward ends of the track sections 59. In this way, a continuous track results, on which the curtains can be drawn around the entire space to be enclosed. Each section of the track is composed of two parallel strips 61 which are separated by a slot and spaced below the top supporting surface by the aid of spacers 62. At the curves rollers 63 are mounted, projecting downward from the box 10, at 30 the top of the fixture, to aid the curtain in being worked around the corners.

The curtain is furnished with eyes 64, which are swiveled in buttons 65, which are so designed as to slide readily in the tracks 35 above the strips 61 and between the spacers 62. The buttons 65 have horizontal holes 66 through them, through which a draw-string 67, one for each curtain, passes. This draw-string 67 is secured by knotting or other means 68 to the first or front button and slides in the remainder. At the back it passes over a pulley 69, and thence downward to a weight 70, said weight being sufficiently heavy to draw the curtain closed 45 when it has been released from the catch 71 at the front of the fixture. This catch preferably consists of a withdrawable pin, which engages hooks 73 secured to the forward ends of the curtains, the pin having 50 a knob on its forward end and passing through the middle of the front portion of a depending marginal flange 72 of the top section 10, which conceals the track. The draw-strings at this region pass over a small 55 pulley or pulleys 74 and have small weights 75 to keep them from getting tangled.

Conveniently located in the columns 4 are buttons and switches 76 to operate the motors and lights. It is desirable under 60 different conditions to have different lighting arrangements, and the fixture is particularly adapted to this end. The lights shown can be of different colors and the switches can take care of different groups; or means 65 such as shown in Fig. 11 can be used for a

colored or modified lighting effect. In this view a removable frame 77 is shown, bearing a sheet 78 of colored silk, celluloid, glass, or other suitable material, and held frictionally against the glass in one of the various 70 light openings of the device. Similar screens can be used in any or all of the light openings, or other embodiments of means may be used to accomplish the same purpose.

Drawers 79 with ornamental handles 80 75 may be inserted at convenient places for the reception of small parts or articles.

From the foregoing it is believed that the preferred construction and mode of operation of the device will be clearly understood. 80 Numerous changes and re-arrangements may be made without departing from the essentials of the invention.

What I claim as new is:

1. A garment display fixture having a 85 back, and a top, a transverse rod supported beneath the top in position to receive garment hangers at right angles to the back, and curtains to cover the open sides and front, said top comprising fixed and movable sections, the movable section being adapted to fold back on the fixed section or to extend forwardly therefrom at will, there being means on the fixed section for supporting the curtain clear of the movable 90 section.

2. A garment display fixture having a 95 back, and a top, a transverse rod supported beneath the top in position to receive garment hangers at right angles to the back, 100 and curtains to cover the open sides and front, said top comprising fixed and movable sections, the movable section being adapted to fold back on the fixed section or to extend forwardly therefrom at will, and lighting means carried by both sections.

3. A garment display fixture having a 105 back, a top, a transverse rod supported beneath the top in position to receive garment hangers at right angles to the back, and curtains to cover the open sides and front, said top including a section bearing lighting means and adapted to extend forward or to be moved back at will, in both positions being above the rod.

4. A garment display fixture having a 110 back, a top, and curtains to cover the open sides and front, said top including a fixed rear section and a hinged forward section adapted to be folded back on top of the rear section, there being means on the rear section for supporting the curtains clear of the hinged section.

5. A garment display fixture having a 115 back, a top, and curtains to cover the open sides and front, said top comprising fixed and movable light boxes with illuminating means therein and windows, adapted to form a short or extended top at will.

6. A garment display fixture having a 120

back, a top, and curtains to cover the open sides and front, said top comprising a fixed rear light box with illuminating means therein and windows in its bottom and front, and another light box movably mounted to form a forward extension or to fold over upon the rear box, at will, the latter box likewise having windows in its bottom and vertical walls.

10 7. A garment display fixture having a back, a top, and curtains to cover the open sides and front, said top comprising a rear, fixed and a forward, foldable light box, having windows in their bottoms, and another 15 light compartment beneath the rear portion of the rear light box, having windows in its front and bottom.

8. In a garment display fixture having a back and top, and open front and sides to 20 be closed by curtains, a forward extension top section movably mounted so as to fold back, and mechanism for operating said section.

9. In a garment display fixture having a 25 back and top, and open front and sides to be closed by curtains, a forward extension top section movably mounted so as to fold back, and mechanism for operating said section comprising a motor, operating connections between the motor and extension section, and a manually operated reversible control means.

10. In a garment display fixture having a back and top, and open front and sides to 35 be closed by curtains, a forward extension top section movably mounted so as to fold back, and mechanism for operating said section comprising a motor, operating connections between the motor and extension section, and a manually operated reversible control means, and means whereby the mechanism automatically disconnects the drive in respect to each limit of movement.

11. A garment display fixture having a 45 back and top, and open front and sides to be closed by curtains, said top comprising a fixed rear section containing lighting means and operating mechanism, and a forward, foldable extension section also provided with lighting means and connected with the operating means in the rear section.

12. A garment display fixture having a back and top, and open front and open sides to be closed by curtains, said top comprising 55 a fixed rear section bearing operating mechanism, and a forward foldable extension section operatively connected with the mechanism of the rear section.

13. A garment display fixture having a 60 back and top, and open front and sides to be closed by curtains, said top having a hinged forward extension section hinged to fold over upon the rear portion, operating means comprising swinging arms slidably and pivotally connected to the hinged section, and

mechanism for operating said arms in opposite directions.

14. A garment display fixture having a back and top, and open front and sides to be closed by curtains, said top having a hinged forward extension section hinged to fold over upon the rear portion, operating means comprising a transverse shaft in the rear portion of the top, a motor and reversible control means for operating said shaft in opposite directions, and arms on the ends of said shaft having pivotal and sliding connection with the hinged section. 70 75

15. A garment display fixture having a back and top, and open front and sides to 80 be closed by curtains, a transverse hanger rod beneath the top, and means in the top for rotating said rod about its axis.

16. A garment display fixture having a back and top, and open front and sides to 85 be closed by curtains, a transverse hanger rod beneath said top, a motor, and connections between the motor and rod for rotating the same.

17. A garment display fixture having a 90 back and top, and open front and sides to be closed by curtains, said top comprising a fixed rear section and a foldable forward extension section, a rotatable hanger rod beneath the top, and means in the rear section for operating the forward section and for rotating said rod. 95

18. A garment display fixture having a back and top, and open front and sides to 100 be closed by curtains, a transverse hanger rod, and means for rotating said rod.

19. A garment display fixture having a back and top, and open front and open sides to be closed by curtains, a transverse hanger rod supported beneath the top within the 105 curtain enclosure, and extension rods adapted to be pulled out from the ends of said hanger rod when the curtains are drawn back.

20. A garment display fixture having a 110 back and top, and open front and sides to be closed by curtains, said top comprising a fixed rear section and a forward foldable section, track sections upon said top sections adapted when the forward section is extended to form a complete track extending across the front and rearward at the sides, and curtain supports movable on said track. 115

21. A garment display fixture having a back and top, and open front and sides to 120 be closed by curtains, said top comprising a fixed rear section and a forward foldable section, track sections upon said top sections adapted when the forward section is extended to form a complete track extending 125 across the front and rearward at the sides, two sets of curtain supports movable on said track, and draw-strings connected to the forward supports of the sets and slidably in the others. 130

22. A garment display fixture having a back and top, and open front and sides to be closed by curtains, said top comprising a fixed rear section and a forward foldable section, track sections upon said top sections adapted when the forward section is extended to form a complete track extending across the front and rearward at the sides two sets of curtain supports movable on said track, draw-strings connected to the forward supports of the sets and slidable in the others, and weights at the rear ends of said strings adapted to draw the curtains back. 60
- 15 23. A garment display fixture having a back and top, and open front and sides to be closed by curtains, said top comprising a fixed rear section and a forward foldable section, track sections upon said top sections adapted when the forward section is extended to form a complete track extending across the front, and rearward at the sides, two sets of curtain supports movable on said track, means tending to withdraw the curtains, and a releasable catch for the forward ends of the curtains. 70
- 20 24. A garment display fixture having a back and top, and open front and sides to be closed by curtains, said top comprising a fixed rear section and a forward foldable section, track sections upon said top sections adapted when the forward section is extended to form a complete track extending across the front and rearward at the sides, two sets of curtain supports movable on said track, means tending to withdraw the curtains, and a releasable catch for the forward ends of the curtains, said catch comprising hooks on the curtains, and a member for engaging both hooks. 75
- 25 25. A garment display fixture having a back and top, and open front and sides to be closed by curtains, said top comprising a fixed rear section and a forward foldable section, track sections upon said top sections adapted when the forward section is extended to form a complete track extending across the front and rearward at the sides, two sets of curtain supports movable on said track, means tending to withdraw the curtains, and a releasable catch for the forward ends of the curtains, said catch comprising hooks on the curtains, and a withdrawable pin supported in the middle of the front of the fixture to engage both hooks. 80
- 30 35 40 45 50 55 26. In a garment display fixture having a back and top, and open front and sides to be closed by curtains, a forward extension top section tiltably mounted to swing up and back, and mechanism for moving and holding said top section in any desired position. 65
27. In a garment display fixture, a forward extension top section having lighting means and being tiltably mounted to swing up and back, and means for holding said top section in any desired position. 70
28. A garment display fixture having a back and open sides and an open front, a top comprising a fixed rear section and a hinged front section adapted to fold up and back, said sections carrying lighting means adapted to throw light downward and forward, a transverse hanger-rod supported below the forward part of the fixed rear section, and curtains adapted to close the open front and sides and to be drawn back clear of the hinged section. 75
29. A garment display fixture having a back and open sides and an open front, a top comprising a fixed rear section and a hinged front section adapted to fold up and back, the foldable section carrying lighting means, the rear section also having lighting means in its top and lighting means below its back portion, a transverse hanger-rod supported below the forward part of the fixed rear section, and curtains adapted to close the open front and sides and to be drawn back clear of the hinged section. 80
30. A garment display fixture having a back and open sides and an open front, a top comprising a fixed rear section and a hinged front section adapted to fold up and back, the rear section having lighting means in its top and a dropped back compartment having windows and containing additional lighting means, a transverse hanger-rod supported below the forward part of the fixed rear section, and curtains 100 adapted to close the open front and sides and to be drawn back clear of the hinged section. 90
31. A garment display fixture having a back and open sides and an open front, a top comprising a fixed rear section and a hinged front section adapted to fold up and back, the rear section comprising a light box containing lighting means and having windows in the front and in the forward part 105 of its bottom and a dropped rear compartment also having windows and containing lighting means, a transverse hanger-rod supported below the forward part of the fixed rear section, and curtains adapted to close the open front and sides and to be drawn back clear of the hinged section. 110
